CRIBBING MACHINE

Dennis M. Praytor and Knox Kershaw,
Birmingham, Ala.

Application December 1, 1945, Serial No. 632,248

7 Claims. (Cl. 37—104)

1

This invention relates to a machine for removing rock and ballast from between railroad cross ties, more commonly referred to as a cribbing machine, and has for an object the provision of apparatus of the character designated which shall be simple and rugged of construction, economical in operation, and one which may be self-propelled.

A further object of our invention is to provide a cribbing machine including a main frame upon which the working parts of the machine are mounted, and a supplementary frame supporting a substantial proportion of the weight of the apparatus and which is adjustable with respect to the main frame to set the digging unit at the required depth.

A more specific object of our invention is to provide a cribbing machine of the character designated which shall include a main frame supported on one rail of the railroad track, and a transversely extending frame having a power unit mounted thereon near one end and digging mechanism mounted thereon near the other end. A supplementary frame is disposed between the digging unit and the main frame and connected by hydraulic jacks to the main frame and is provided with supporting wheels having pneumatic tires, the supplementary frame being adjustable vertically by means of the hydraulic jacks with respect to the transverse frame, whereby the digging unit may be set at various depths.

As is well known in the art to which our invention relates, in relaying railroad rails, particularly with heavier rails, when the lighter rail has been removed, the cross ties from which it has been removed must be trimmed with an adzing machine to fit the tie plates employed with the new rail being laid. In order to use the adzing machine, it is necessary that all rock and ballast be removed from between the cross ties at that location. After ballast has remained in a railroad track for a period of years and has become thoroughly packed down, it is a very laborious operation to remove it manually, so much so that it is prohibitive in cost. It is accordingly a principal object of our invention to provide a simple, rugged, and relatively inexpensive machine which shall be adapted to be propelled by its own power on one rail of the railroad track and partially supported thereon, with a substantial portion of its weight supported by adjustable supplementary wheels traveling on the ground, and having a digging unit adapted to fit down between the ties where one rail has been

2

removed and quickly remove the rock and ballast from between the ties on that side of the track.

Apparatus embodying features of our invention is illustrated in the accompanying drawings, forming a part of this application, in which

Fig. 1 is a plan view with certain parts removed, the better to illustrate the invention;

Fig. 2 is a sectional elevation taken along the line II—II of Fig. 1;

10 Fig. 3 is a sectional view taken along the line III—III of Fig. 2;

Fig. 4 is a sectional view taken generally along the line IV—IV of Fig. 2; and

15 Fig. 5 is a detailed perspective view of a portion of the digging unit.

Referring now to the drawings for a better understanding of our invention, we show in Fig. 1 a railroad road bed including cross ties 10 and one rail 11, the other rail having been removed. The 20 machine comprises longitudinal main frame members 12 and 13 formed from structural steel beams. Mounted between the frame members 12 and 13 are a pair of wheels 14 and 15 having axles 17 and 18 mounted in suitable bearings carried by the frame members. The axle 17 extends inwardly of the road bed through the frame member 13 and carries on its inner end a sprocket 19 by means of which the machine is propelled on the track.

25 30 35 40 45 50

Mounted over the longitudinally extending frame is a transverse frame comprised of frame members 21 and 22 which are supported by the frame members 12 and 13. The transverse frame extends across the road bed with one end overhanging the tie plate seat 23 in the cross ties. Secured to the under side of the frame members 21 and 22 are longitudinally extending structural beams 24 and 26.

The machine is in part supported by a supplementary frame comprised of longitudinally extending members 27 and 28 between which are mounted pneumatic tired wheels 29, 31, 32, and 33 on axles 34, 36, 37, and 38, mounted in suitable bearings carried by the beams 27 and 28. As may be seen from Fig. 3 of the drawings, the wheels 29, 31, 32 and 33 are so spaced that in whatever position the machine may be on the road bed, two of the said wheels will be resting on cross ties 10. Spanning the longitudinally extending supplementary frame members 27 and 28 are plates 39 and 40 disposed, respectively, near the opposite ends of the supplementary frame. Corresponding plates 30 and 35 span the members 24 and 26. A hydraulic cylinder 41 is pivotally mounted at 42 on the plate 30 and its associated plunger 42 is

carried by the plate 38. A second hydraulic cylinder 43 is pivotally mounted on the plate 35 over the plate 39 and its associated piston member 44 is carried by the plate 39. Fluid under pressure for operating the cylinders is supplied through conduits 50 and 50' controlled by a valve 45. By means of the hydraulic cylinders 42 and 44, the elevation of the transversely extending frame with respect to the supplementary frame may be adjusted. The longitudinally extending supplementary frame members 27 and 28 are pivotally connected to the main frame members 12 and 13 by means of links 51 and 52. The link 51 is connected by means of a pin 53 to a bracket 54 mounted on the longitudinally extending frame member 13. At its other end, the link 51 is connected to the supplementary frame by a pivotal connection 56 with the end of the axle 38. The link 52 is similarly connected to the opposite end of the frame member by means of a pivot pin 57 and bracket 58, mounted on the main longitudinally extending frame member 13 and at its opposite end by means of a pin 59 to the end of the axle 34.

Mounted on the end of the transverse frame, overhanging the road bed adjacent the tie plate seat 23 is a rotary digging unit having an axle 61 extending transversely of and mounted in bearings 62 and 63, carried by the frame members 21 and 22, respectively. The digging unit comprises a wheel 64 mounted on the axle 61 and having teeth 66 mounted on its periphery. The teeth 66, as may be seen in Figs. 1 and 5 of the drawings, are inclined to the rim, alternately, with one inclined in one direction and the succeeding one in the other direction. The teeth are welded to the rim of the wheel 64 and each is provided with adjustable points comprised of rods 67 which pass through holes in the rim of the wheel and are held in place on the teeth 66 by means of U bolts 68. As is well understood, rock and ballast are very abrasive and by the means shown, as the points 67 are worn away, the rods may be pushed further outwardly to renew them.

At 71 we show an internal combustion engine of the type usually employed to drive motor vehicles. A clutch 72 and a well known form of three-speed and reverse transmission 73 transmits power to a drive shaft 74. The clutch is operated by means of a lever 76 and the transmission by means of a lever 77. At 78 is indicated the usual power take-off associated with engines of the type indicated which is controlled by means of a lever 81 to drive a shaft 82 having a sprocket 83 mounted thereon which connects with the sprocket 19 on the axle 17 by means of a sprocket chain 84, whereby the apparatus may be propelled on the rail 11 in either direction, as desired.

The drive shaft 74 drives a countershaft 86 by means of bevel gears 87 and 88. The countershaft 86 is mounted in suitable bearings 85 on the frame members 21 and 22 and has mounted on its ends V belt pulleys 89 and 91, which drive the axle 61 of the digging unit through the medium of V belts 92 and 93 and pulleys 94 and 96 mounted on the ends of the axle 61.

From the foregoing description, the operation of our improved cribbing machine will be readily understood. When rails are being relaid, it is contemplated that they will be relaid on one side of the track at a time, for a predetermined distance. The apparatus is mounted with the flanged wheels 14 and 16 on the rail 11, as shown in Figs. 1 and 2 of the drawings, and the digging

unit 64 is positioned between a pair of ties from which the ballast is to be removed. The hydraulic cylinders 41 and 43 are operated by means of the valve 45 to lower the digging unit so that the teeth 66 engage the rock and ballast, the digging unit being driven by means of the power unit 71. It will be seen that by means of the hydraulic cylinders and their associated plungers, the unit can be gradually fed into the work as it is being performed. It will be noted that the operating handles for the clutches, the transmission, and the valve 45 are located so as to be accessible to an operator's seat 97. Thus, one man, seated in the seat 97, can operate the machine. Whenever it is desired to move the apparatus from place to place, or to re-position it with the digging unit between the ties, the power take-off lever 81 and the transmission lever 77, are manipulated to move the apparatus in the proper direction and at the desired speed.

The apparatus is so designed that substantially one half the weight thereof is carried by the main frame and wheels 14 and 16, and the other half by the supplementary frame and wheels 29 to 33 inclusive. Whenever the transverse frame is raised with respect to the supplementary frame, by means of the hydraulic cylinder, there is necessarily a very slight lateral movement of the wheels 29 to 33 with respect to the ties but this is minimized by reason of the pivotal mounting of the supplementary frame and its pivotal connection with the main frame. The resistance to this slight movement is further minimized by the pneumatic tires on the wheels 29 to 33.

It will accordingly be apparent that we have devised an improved cribbing machine which is simple and rugged of design, easily manipulated, and one which may be readily positioned and adjusted for the work to be done.

While we have shown our invention in but one form, it will be obvious to those skilled in the art that it is not so limited, but is susceptible of various changes and modifications, without departing from the spirit thereof, and we desire, therefore, that only such limitations shall be placed thereupon as are specifically set forth in the appended claims.

What we claim is:

1. In a cribbing machine for removing ballast from between the cross ties in a railroad roadbed, a main longitudinal frame having flanged supporting wheels adapted to travel on one rail, a transverse frame rigidly secured to the main frame and having one end overhanging the other side of the roadbed, a supplementary frame pivotally connected to the longitudinal main frame and adjustably connected to the underside of the transverse frame intermediate the ends thereof, supporting wheels on the supplementary frame, and a power driven digging unit carried by the overhanging end of the transverse frame and disposed to remove ballast from between the ties.

2. In a cribbing machine for removing ballast from between the cross ties in a railroad roadbed, a main longitudinal frame having flanged supporting wheels adapted to travel on one rail, a transverse frame rigidly secured to the main frame and having one end overhanging the other side of the roadbed, a supplementary frame pivotally connected to the longitudinal main frame and adjustably connected to the underside of the transverse frame intermediate the ends thereof, supporting wheels on the supplementary frame, and a power driven digging unit carried by the overhanging end of the transverse frame and

disposed to remove ballast from between the ties, the supplementary frame supporting approximately half the weight of the machine.

3. In a cribbing machine for removing ballast from between the cross ties in a railroad roadbed, a main longitudinal frame having flanged supporting wheels adapted to travel on one rail, a transverse frame rigidly secured to the main frame and having one end overhanging the other side of the roadbed, a longitudinally extending supplementary frame disposed beneath the transverse frame intermediate the ends thereof, supporting wheels for the supplementary frame, a flexible connection between the supplementary frame and the main frame, adjustable hydraulic cylinders and pistons connecting the supplementary frame and the transverse frame, a power unit on the transverse frame, a rotary digging unit on the overhanging end of the transverse frame, and change speed and reverse power transmission means between the power unit and the digging unit.

4. Apparatus as defined in claim 3 in which the supplementary frame is provided with a plurality of supporting wheels so spaced that at least two wheels are at all times resting on cross ties, and in which the supplementary frame is so disposed as to support substantially half the weight of the machine.

5. Apparatus as defined in claim 3 in which the supplementary frame is provided with a plurality of supporting wheels having pneumatic rubber tires and so spaced that at least two wheels are at all times resting on cross ties, and in which the supplementary frame is so disposed as to support substantially half the weight of the machine.

6. In a cribbing machine for removing ballast from between the cross ties in a railroad roadbed, a main longitudinal frame having flanged supporting wheels adapted to travel on one rail,

a transverse frame rigidly secured to the main frame and having one end overhanging the other side of the roadbed, a longitudinally extending supplementary frame disposed beneath the transverse frame intermediate the ends thereof, supporting wheels for the supplementary frame, a flexible connection between the supplementary frame and the main frame, adjustable hydraulic cylinders and pistons connecting the supplementary frame and the transverse frame, a power unit on the transverse frame, a rotary digging unit on the overhanging end of the transverse frame, and change speed and reverse power transmission means between the power unit and the digging unit.

7. In a cribbing machine for removing ballast from between the cross ties in a railroad roadbed, a main longitudinal frame having flanged supporting wheels adapted to travel on one rail, a transverse frame rigidly secured to the main frame and having one end overhanging the other side of the roadbed, a longitudinally extending supplementary frame disposed beneath the transverse frame intermediate the ends thereof, supporting wheels for the supplementary frame, a flexible connection between the supplementary frame and the main frame, adjustable hydraulic cylinders and pistons connecting the supplementary frame and the transverse frame, a power unit on the transverse frame, a rotary digging unit on the overhanging end of the transverse frame, change speed and reverse power transmission means between the power unit and the digging unit, and power transmission means for selectively connecting the power unit to one of the supporting wheels for the main frame.
